UNITED STATES PATENT OFFICE.

JOSEPH J. PILGER, OF COVINGTON, KENTUCKY.

CANDY-BOX.

1,293,910.

Specification of Letters Patent.

Patented Feb. 11, 1919.

Application filed February 28, 1918. Serial No. 219,595.

To all whom it may concern:

Be it known that I, JOSEPH J. PILGER, a citizen of the United States, and a resident of Covington, in the county of Kenton and 5 State of Kentucky, have invented certain new and useful Improvements in Candy-Boxes, of which the following is a specification.

My invention relates to boxes, and more 10 especially to the interior construction thereof. Its object is to enhance the appearance of the box when it is actually in use as distinguished from when it is only stored or displayed for sale, and to also facilitate the identification of the maker of or 15 dealer in the contents of the box while the box is thus in use. A further object is to accomplish the just-stated objects without lessening the convenience of use of the box 20 or of access to the contents thereof; but rather to facilitate such access and increase such convenience; as well as to afford a better protection to the contents when the box is closed.

25 My invention consists in the combination of parts and in the details of construction and arrangement of parts and in the new and improved article of manufacture as will hereinafter be more fully described and 30 claimed.

In the drawing:

Figure 1 is a perspective view of a candy box embodying my invention with the cover removed and not shown, and with the mat 35 raised to permit access to the contents of the box and for display of its ornamental and identifying matter;

Fig. 2 is a vertical cross-section on a plane corresponding to the line 2—2 of Fig. 1;

40 Fig. 3 is a corresponding cross-section, but showing the box closed with its lid thereon;

Fig. 4 is a detail perspective view of part 45 of the mat before it is applied to the box to better illustrate how it is creased; and

Fig. 5 is a perspective view similar to Fig. 1 showing the mat down and the lid ready to be applied.

As I have chosen to exemplify my invention, it is embodied in a box 1 of elongated 50 rectangular formation open at its top, and having a lid 2 of corresponding formation open at its bottom and inversely fitted there-over as is usual and well known in the construction of candy boxes. Also, as is well

known, this box contains the pieces of candy generally in orderly layers or series such as the pieces 3 and 4 in a lower and an upper layer, respectively, and with a sheet of paper 5 or other suitable material interposed between the layers. 60

It will be understood, however, that boxes of various styles and shapes, containing candy or confections of various kinds and shapes, and placed therein in various arrangements or with various other protective, ornamental or other interior details, may have my invention applied thereto. The more expensive the candy or other contents, the more elaborate, generally, are the protective and ornamental details of the interior of the box, as is also the box itself. 70 My invention is adaptable in connection with any of these as will be understood from the description in connection with this example. 75

Over the top layer under the lid, it has been customary to fold what are called "laces" from the opposite upper edges of the box to the inner sides of which, adjacent to these upper edges, these laces have edge parts pasted; and the laces being suitably caused to fold down over the candy. Usually these laces do not meet along the middle of the box, but leave one or more rows of the 85 candy near the middle of the box exposed to view, as soon as the lid 2 is taken off.

Also in some candy boxes, instead of or with the separate laces hinged to opposite side parts of the box and coming more or less closely together along the middle of the box over the candy, such boxes have been provided with "mats." The mat, so far as I am aware, is not attached to the box at all; but merely is laid in the box over the 95 candy and reaches the major part of the way across the box.

The "laces" and the "mats" usually have ornamentation on them; the "laces" being made from paper or other suitable material 100 with interior parts of it cut away according to various ornamental designs, giving the part the appearance of lace as its name implies; the "mats", however, are only embossed with ornamental designs. It is this 105 distinction rather than the degree of extension across the box or the number of them used in a box that distinguishes the "laces" from the "mats"; although, as before stated, the mat is loose and in one piece extending 110

nest of the way across the box, and the laces are made in two pieces attached to and extending from opposite sides of the box to near the middle thereof.

5 Whatever these parts may be called, or whatever their relative number in a box, or degree of extension, it nevertheless seems that their only well recognized function heretofore has been to produce momentarily 10 upon first opening the box a decorative effect as seen from their outer or upper sides as they lie down upon the candy, to be lost sight of as soon as the "laces" are folded back off the candy, or as soon as the mat is removed.

15 Quite frequently the laces are torn from the box, and the mats, being detached from the box, are taken out and thrown away, when access is had to the candy for the first time.

According to my invention, the part of the 20 box corresponding to the lace or mat 6 of the usual boxes just now described is preferably made in one piece wide enough and long enough to extend fully across and from one end to the other of the interior of the box 25 over the candy 4 with its edges 7 fitting snugly against the inner sides of the box near its upper rim or edge all around. The mat 6 thus proportioned and arranged has along one of its edges a flap 8 formed by 30 scoring the mat to form this flap 8 which is pasted or otherwise suitably secured preferably to the inner surface of the box along near one of its upper edges. As here shown, this creased flap 8 is provided along one of 35 the longitudinal edges of the mat, so that the mat is attached and hinged to one of the longer sides of the box. Also, as here shown, this flap 8 is secured to the inner surface of 40 this side of the box. It is preferred to have the mat attached on the inner side of the box, because then the mat folds down snugly 45 across the candy, and at the same time, when raised, is held in upright position because of the reluctance of the mat material to stretch where it has been scored, which stretching 50 would be necessary in order for the mat to bend farther back and down over the outside of the box.

With the parts thus properly proportioned 55 and arranged, the mat 6, when raised, will stand in upright position or lean slightly out over the outside of the box, as shown in Figs. 1 and 2; or may be folded down and across the top of the candy 4, forming a substantially complete inner cover for the candy 60 immediately before the cover or lid 2 is placed on the box, or immediately after said cover is removed from the box. The relative positions of these parts is well indicated in 65 the section in Fig. 3 where the mat 6 is seen lying across the top of the candy and the cover down thereover, and in Fig. 5 with the cover removed.

As is well known, the covers of candy 70 boxes, on their exteriors, are nearly always

provided with some form of ornamentation, or at least with some mark of identification; and generally with ornamentation and identification marks together. Also, as before stated, the "laces" or "mats" or other parts 70 placed inside the box, are generally ornamented by embossing or imitation of lace work, or otherwise, on their outer sides which are exposed immediately when the cover is removed from the box; but their being ornamented or otherwise treated does not cause them to attract favorable attention on their inner or under sides which are exposed when the laces are raised away from the candy, if indeed such laces are not immediately torn 75 off and thrown aside, because of their unattractiveness when thus inverted and caused to lie out over the sides of the box. Also, as before stated, the mats are not attached to the box at all, and whatever their ornamentation, they have no definite association with the box immediately after the lid is removed and access is had to the candy; because the natural impulse for almost every one is to remove this loose covering and throw it 80 aside.

If any such provision, it is to be recognized that the primary purpose of the person opening the package usually is to have access to the contents; any coverings or ornamental effect incidentally encountered immediately after opening the box and before access to the contents is usually only very imperfectly appreciated; although, of course, having its merit even though the user of the 95 box and its contents be impressed by it unconsciously. Such dainty ornamental effects as may be produced by these "laces" or "mats" add to the attractiveness of the candy itself, because surrounding it with details that appeal to the sense of sight much as the candy does to the sense of taste; and also emphasizing the policy of cleanliness which accompanies the production and marketing of the candy. But such impressions 100 with the "laces" or "mats" as heretofore provided, so far as I am aware, have only been momentary. They endure only for the very brief interval after the lid or cover 105 has been withdrawn and they are exposed to view, to the time when these "laces" or "mats" are raised or thrown away in the act of exposing the candy to view and to the reach. Such act of exposing to the view 110 and the reach of the user is generally eagerly rather than hesitatingly accomplished; and it is a matter for practical consideration that such ornamental details as are presented by these "laces" or "mats," have a period of usefulness in the average candy box of only 115 one or two seconds.

It is the purpose of my invention to obtain for this detail of the candy box construction a greater period of usefulness and a more substantial usefulness than it has heretofore 120

had after the lid or cover has been removed and in the process of or after the getting of access to the candy.

I accomplish this by providing the mat, 5 with its ornamentation on its outer or upper side, with attachment to the box so that when it stands in upright position, as hereinbefore described, the reverse of this ornamentation is in full display immediately at one 10 side and extending up from the candy in the box. Also, preferably, I place the name of the maker of or dealer in the candy on this lower or inner side of the mat. Thus, as seen in Fig. 1, the name 9 occupies the central 15 part of the mat and is flanked by suitable ornamentations 10 in the opposite end parts of the mat and at the bottom and top below and above the name; but this name being on the lower or inner side of the mat so that it 20 is in full view while the candy is being taken from the box.

As here shown, this mat is provided with scallops 11 around its ends and its free edge, with embossed simulations 11' thereof along 25 its attached edge. It is preferably so proportioned that it fits snugly against the box sides when it is folded down. It will be understood, of course, that the mat may have plain edges.

30 The name or identification mark 9 may be merely printed on the inner or lower surface of the mat 6 in one or more colors. It is preferably not embossed so as to leave to the upper or outer side a plain surface opposite where the name or mark is provided, as 35 seen in Fig. 5.

The mat being so constructed that it will remain in an upright position substantially like that of Figs. 1 and 2 and not droop 40 down over the outside of the box or fall back down on the candy, the incentive to remove or destroy it is practically eliminated. This is on account of the absence of objectionable obstruction incident to this self-supporting 45 operation of the device as compared with the indifferent self-sustaining properties of the laces as they usually have been provided.

Thus, the amount of labor and expense devoted to the beautifying of these inner details of candy boxes, instead of being of 50 merely momentary appreciation, now becomes something to be noticed more frequently and to generally be as permanent as any of the other details of the box. That is 55 to say, my improved mat or the like, with a self-sustaining function and display matter appearing reversely on its inner or lower side adjacent to the box contents, is adapted generally to endure at least until the contents of the box have been exhausted.

60 Thus, so far as concerns supplementing by the sense of sight what candy supplies by sense of taste, there is a more perfect realization of this as a result of the labor and expense imposed on these inner details of the

candy box, because of the greater permanence of the details during the use of the box and the contents. When the candy box is opened and the candy is being taken therefrom, the lid, generally being separated from 70 the box, is laid aside and generally not seen or thought of again until there has been removed such of the contents as is desired, and it is intended to replace the lid or cover. During such removal and while the candy is 75 being taken from the box, the name or identifying mark on the outside of the lid is thus generally out of view of the user, and is thus not intimately associated with the candy or other contents of the box at the very time, if 80 the qualities of the candy or other contents is an asset to the maker of or dealer in such contents, when the name or identifying mark of this dealer or maker should be as nearly as is possible unavoidably recognizable in 85 connection with the contents.

With my invention, this last stated requirement is fulfilled. Whether the user of the candy alone have access to the box or whether it be passed around to others, the 90 self-sustaining properties of the mat or the like and the attractiveness of its inner or lower side in its raised position are such as to practically in all cases insure that this mat will be retained on the box in this up- 95 right position with the name or mark of the dealer or maker in full display immediately adjacent to the candy; so that anyone taking candy from the box will almost inevitably see this name or mark. It will thus be seen 100 that the advertising value of the container is very much enhanced by this provision; and this not alone but in connection with a more perfect realization of the functions which these mats, laces or the like heretofore 105 had, i. e., the better protection of the box contents when the box is closed and a more permanent provision of the appetizing influences of the dainty interior details in close association with the contents.

110 Preferably, the mat or element 6 is scored in two places along near one of its edges in spaced apart positions on opposite sides of the element 6, so that the flap 8 is formed joining a shoulder 12 by means of the hinge 115 constituted by the crease 13 made by the scoring nearer the edge of the element; and said shoulder 12 joining the major part of the element 6 by the other crease 14. Preferably, this other crease 14 is not made as deep 120 as the crease 13; so that once the major part of the element 6 is bent nearly at right angles to the shoulder 12, these parts tend to maintain these relative positions and the swinging of the element is on the other crease 13. 125 The flap 8 is suitably secured as by pasting to the interior side of the wall of the box 2 with the hinging crease or scoring 13 substantially coincident with the upper edge or rim of the box wall. Thus, when the ele- 130

45
ment 6 is raised and thrown over to the side of the box, its shoulder 12 engages with this upper edge or rim of the box wall to sustain the element 6 in this upright position for 5 the display of the matter on its inner or lower side adjacent to the interior of the box and the candy 7 contained therein.

It will be understood that although I have alluded to the element 6 as a "mat" because, 10 in the form in which I prefer to provide it, it is similar in many respects to the candy box detail heretofore known by that name; it is not essential that this element 6 should respond in every respect to the description 15 of a "mat"; but may have any kind or ornamentation desired, whether plain printing, embossing, "lace" work or combinations of these, or other styles of ornamentation possible if the expense thereof is warranted.

20 It will be understood that on account of the more permanent utility of these details according to my invention, the more expensive forms of ornamentation will be more frequently resorted to in these connections 25 than with the less permanent details of the prior boxes.

Likewise, although I have illustrated a certain relative arrangement of the ornamentation 10 and of the name 9, any desired 30 arrangement comes within the scope of my invention; since it is not to the ornamental design, but to the mechanical details of construction and arrangement governing the use of the design, that my invention is directed. And, as before alluded to, the shape 35 or proportions of the box 1 and the location of the attachment or hinging of the element 6 thereto, while generally preferred, as herein shown, may be departed from as circumstances may require; and so in many other 40 minor details considerable modification is possible and may be necessary in adapting my box to use under varying conditions.

Therefore, although I have shown and 45 described certain details rather specifically in elucidating the construction and use of my invention as is required, I do not wish to be understood as being limited to such precise showing and description, but having 50 thus fully described my invention, what I claim as new and desire to secure by Letters Patent is:

1. In combination with a candy box or the like, and a lid therefor slidably fitting 55 down thereover, an element of material

adapted to be folded by scoring, said element being scored, whereby a hinge is formed between a main part and a foldable flap, said flap being attached to the interior side of one of the walls of said box with 60 its hinge adjacent to the upper edge or rim of said wall whereby said main part of said element is hinged to said wall and adapted to be swung down in the upper part of the interior of said box under the lid thereof 65 when said box has its lid fitting down thereover, and to remain in said swung-down position while said lid is withdrawn from said box, but adapted to be manually swung up on said wall, said hinge being so formed 70 that said main part is supported in its upwardly swung position by said hinge, and display matter obversely appearing on the side of said element that is adjacent to the interior of said box when said element is 75 swung up on said wall, as aforesaid.

2. The combination with a candy box or the like, and a lid slidably fitting down over said box to close its top, an element of material adapted to be folded by scoring, said 80 element being scored in spaced apart locations on opposite sides whereby a shoulder is formed, joining a main part and a foldable flap, said flap being attached to the interior side of one of the walls of said box 85 with its scoring that is between said flap and said shoulder adjacent to the upper edge or rim of said wall, whereby said main part of said element is hinged to said wall and adapted to be swung down in the upper part 90 of the interior of said box under the lid thereof when said box has its lid in closing position, and to remain in said swung-down position while said cover is withdrawn upwardly, and to be manually swung up on 95 said wall with its shoulder resting down on said upper edge or rim of said wall when said lid has been moved to an opening position, and to be supported in its upwardly swung position by said shoulder resting on 100 said upper edge or rim of said wall, and display matter obversely appearing on the side of said element that is adjacent to the interior of said box when said element is 105 swung up on said wall, as aforesaid, substantially as and for the purposes specified.

JOSEPH J. PILGER.
